DISPENSING PACKAGE

Charles J. Haag, Hohokus, N. J.

Application June 2, 1944, Serial No. 538,466

15 Claims. (Cl. 206—42)

This invention relates to dispensing packages and related devices.

One object of the invention is to provide a dispensing package especially adapted for pills, hard candies, and other articles, having an improved tubular construction with means for the individual dispensing of the articles.

Another object of the invention is to furnish a device of the character described having improved means for individually holding and dispensing articles, without permitting the articles to rattle while so packaged.

Another object of the invention is the provision of a device of the nature set forth having improved closure means adapted to be released by the holding pressure of the hand.

Another object of the invention is to construct a device of the type mentioned having improved means to prevent separation of the parts of the package, but permitting easy assembling thereof.

Another object of the invention is to devise an improved structure which is adapted to be molded of plastics with the use of simple dies, with one or more of the parts consisting of transparent material for easy visibility of the contents and their location as dispensing progresses.

Another object of the invention is to furnish improved feeler means to indicate the approach of an article to dispensing position without requiring observation thereof.

Another object of the invention is to construct improved means such that an opening movement causes the contained articles to become loose, and a closing movement causes the articles to be snugly held against rattling in the package.

Another object of the invention is the provision of a dispensing package having improved means for holding a number of articles for individual removal without permitting all the articles to accidentally drop out if they are all moved to dispensing position.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a top plan view of a dispensing package embodying the invention, showing the same in partially open position.

Fig. 2 is a vertical central sectional view thereof with parts in elevation.

Fig. 3 is a vertical sectional view through the closure end of the device when the same is in closed position.

Fig. 4 is a sectional view on line 4—4 of Fig. 2, with an article therein shown in dot-dash lines.

Fig. 5 is a similar view of a modification.

Fig. 6 is a fragmentary sectional view with parts in elevation showing a modification, articles to be dispensed being shown in dot-dash lines.

Fig. 7 is a sectional view corresponding to that of Fig. 3.

Fig. 8 is an end view of the tubular member.

Fig. 9 is a fragmentary plan view of a modification.

Fig. 10 is a transverse section thereof.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 15 denotes a device such as a dispensing package embodying the invention. The same may include a cylindrical cover member 16 open at the end 17 and closed at its opposite end 18. Telescopically slidable in the cover is a carrier member 19 having at one end a closure portion 20 for the cover and having at its opposite end a guide disc 21. The intermediate portion of the carrier or slide member 19 is reduced in size to approximately a half-round cross section which is divided by partitions 22 to form pockets for receiving articles such as 23. Preferably the side walls of the pockets are continued in parallel relation to each other as at 24, beyond the central plane of the device, to a plane indicated at 25. The closure 20 may comprise a knob or finger piece 26 which always lies outside of the cover, and an undercut portion 27 which is adapted to enter the cover to engage the same frictionally or otherwise. Preferably a novel means is provided for releasably locking the closure. This may consist in

providing an irregular contour for the portion 27, as by constructing the opposed flat portions 28 thereon. Now by pressing on the cover 16 as indicated by the arrows 29, the cover is adapted to be deflected to reduce the frictional engagement at the surface 30. In other words, the cover 16 and the closure portion 27 are so proportioned in size as to provide a rather tight fit, with the flats at 28 affording clearance for distortion of the cover into an irregular shape for releasing the closure. That irregular shape may be considered ovoid, like the portion 27. The tightness in the fit may be varied so that the closure may be released by merely pulling thereon; but preferably some pressure is required as at the arrows 29. To facilitate insertion of the portion 27 into the cover, the former may have its leading edge beveled or rounded off. Of course, the main part 31 of the carrier 19 is slightly reduced in size so as not to interfere with the distortion of the cover 16 by the releasing pressure. When the device 15 is closed, the chambered body 31 is carried by the closure and by the end disc 21, and the latter serves as a guide in withdrawing the body from the cover. To prevent separation of the carrier 19 from the cover, the latter may have a small projection 32 at its open end 17 seating in a longitudinal groove 33 in the member 19, which groove is closed ended at the head 26 and adjacent to the disc 21 as at 34. Thus the projection 32 may form a stop, and the thickness of the disc 21 may be sufficient to ensure that it engages the cover and prevents separation of the carrier 19 by a tilting movement when the carrier has been moved outward. The engagement between the stop 32 and groove 33 will also prevent relative rotation between the carrier and its cover which is of advantage if the cover is opaque but which is unimportant if the cover is transparent. In the former case, a suitable marking or other indicia may be used to show where the releasing pressure at 29 should be applied; in the latter case, observation of the carrier through the cover will directly indicate where the releasing pressure should be applied. Also, the prevention of relative rotation avoids the possibility that the stop 32 might come into the path of the articles 23.

By the provision of a carrier 19 having pockets or chambers which closely fit the articles, such as 23, with the same being contacted and retained by the cover 16, rattling of the articles is prevented as where the package 15 is carried in one's pocket. If the cover is transparent, the operator can readily observe the number and position of the articles 23, but if the cover is opaque or if the package is being used in the dark, a feeler may be of advantage to indicate the approach of the leading article 23. Such a feeler may consist of a projection 35 which is rather slight and is adapted for wiping contact with an adjacent edge of an article 23 but in a sufficiently positive manner to afford a frictional obstruction so that the operator may feel the resistance or retardation. Now, by a further small movement of the carrier, the leading article 23 thus engaged passes the feeler 35, and thus only the one article is exposed. If the device 15 is turned, only this one article will drop into the hand, instead of more than one. This operation is readily obtained with hard articles such as pressed pills, hard candies, and other objects and articles that are to be packaged. Of course the feeler 35 may be resilient, and this may be readily accomplished

by thinning down the immediately adjacent wall portion 36 of the cover, if desired, so that that portion becomes sufficiently resilient for this purpose. The portion 27 may have a slight flat or groove 35a to accommodate the feeler in closed position, and the feeler is shallower than 32.

The device 15 can be constructed of metal, plastic or composition materials, having suitable yield or elasticity to the small degree required. Thus it can be molded with the use of simple dies and where projections are employed, they are so small as not to interfere with the stripping of the molded element from the die.

In assembling, the carrier may be tiltingly inserted so that the projection 32 is received in the groove 33 and then the carrier is gradually aligned with the cover while being forced into the latter, with the disc 21 snapping past the projection 35. Now the articles 23 are filled into the carrier and the package is closed by the closure 20, which can be opened by a simple strong pull or, more easily, by pressure as at arrows 29. In either case, there is no such trick lock as would prevent the uninitiated from opening the device, and yet the closure is released by the hand hold on the package. The feeler 35 permits accurate individual removal of the articles 23 and is too small to serve as a stop for the carrier, this function being performed by the larger projection 32.

In Fig. 5 is shown a modification which is like the device 15 except that the carrier 37 is formed a little more than half round, for engaging the articles 38 to prevent them from accidentally dropping out of an exposed pocket, but to permit relatively easy withdrawal of the articles 38 by individually taking hold of them. In other words, the carrier affords only a snug wiping contact with the articles at the edges 39. If the feeler 35 is to be used, it may be suitably lengthened to engage the articles 38 as described.

In Figs. 6 to 8 is shown a modification 40 according to the invention, which embodies all the features of the device 15, but contains improved means such that any tendency to rattling is prevented in a positive manner. This improved means creates a positive pressure or engagement between the articles 23 and the cover 41, automatically effective when the package is closed, and depending upon a motion secondary to or coincident with the main closing movement of the package. In a simple form, this means involves the provision of sloping or cam portions 42 on the carrier 43, and 44 on the cover 41, both being simultaneously operative. Thus the cam 42 engages the mouth portion of the cover, and the cam 44 engages the disc 21 of the carrier 43, both cams serving to cause an upward movement of the carrier relative to the cover, to cause the upper edge portions of the articles 23 to be pressed against the cover. The groove 33 for the stop 32 may slope with the cam 42 as at 45, so that the relatively shallow stop shall not leave the groove and cause jamming. Nor will the feeler 35 interfere, because the lifting of the carrier by the cams 42, 44 does not begin until all the articles 23 are in the cover and have passed the feeler, and the cam 42 is so coordinated with the locking means for the closure as not to interfere with its operation above described. In this case, the cam 42 is a portion of the closure which causes the part 27 to tightly frictionally engage in the cover, release being facilitated as before by pressure on the cover as indicated by the arrows 29. The part 27 may have a recess or groove 46 to afford clearance for

the feeler 35. In releasing, a minute movement will suffice to loosen the contact of the articles 23 with the cover, especially as the articles are able to move laterally or to tilt slightly in their pockets. And the proportions can be so accurately determined that there is no possibility of merely jamming the articles 23 when the package is closed. A pill pressed out in a die can be produced with precision measurements and may be made round, oval, polygonal, and of any other shape.

In Figs. 9 and 10 is shown a device 47 like that at 15 or 40 but showing a carrier 48 in a cover 49, with the carrier having partitions at 50, 51 to provide two rows of pockets which are relatively staggered in the different rows for discharging only one article at a time. Accordingly this cover 49 is rather elliptical in cross section. For each row of articles an individual feeler may be used, but otherwise the structure and mode of operation is unchanged.

It will be appreciated that various features herein shown may be omitted or used in other combinations and arrangements, and this applies to the stop 32, the feeler 35, the locking means at 27, 28, and the cams at 42, 44.

In general, the invention provides a simple, highly compact structure which is both a sales package and a dispenser, adapted to be conveniently carried in one's pocket, and by reason of its tubular form, occupies no more space than a large fountain pen and may be clipped into one's pocket in the same manner.

I claim:

1. A dispensing package including a generally cylindrical tube open at one end, a carrier member having end portions of generally circular cross section adapted to internally fit said tube and having an intermediate portion of reduced cross section comprising a row of pockets for receiving articles to be dispensed, the intermediate portion having a bottom wall for said pockets resting directly on the tube with the mouths of the pockets being spaced from the tube wall so that said articles project from the pockets, one of said end portions constituting a plug for closing the said open end of the tube and the plug having a finger piece for projecting the carrier from the tube.

2. A dispensing package according to claim 1 wherein said plug and said tube provide an irregular frictional surface of engagement affording opposed clearances between the plug and the tube such that external pressure on the sides of the tube at said clearances causes a yielding deformation of the tube to thus release the plug.

3. A dispensing package according to claim 1 wherein the said bottom wall is provided with a closed ended groove, the tube having at its mouth a stop portion projecting into said groove.

4. A dispensing package according to claim 1 wherein said tube is provided at its open end with a feeler portion projecting into the path of the adjacent edge portions of said articles as the latter move to dispensing position to thus afford a momentary frictional retardation to indicate the approach of an article to discharging position, said plug having a recess affording clearance for the feeler in the closed position of the package.

5. A dispensing package according to claim 1 wherein said pockets are more than half round in cross section but only sufficiently so to frictionally engage the articles against dropping out but to yield upon grasping the articles for removal thereof.

6. A dispensing package according to claim 1 wherein said tube is provided with a transparent portion to permit observation of said articles in operating the package for dispensing, the transparent portion extending longitudinally of the row of pockets.

7. A dispensing package according to claim 1 wherein means is provided to cause lateral movement of the carrier as the tube is closed by the plug to thus cause the said articles to press against the tube to avoid rattling thereof, said means being released upon opening said plug, and comprising spaced aligned cam portions of which one is at the plug and the other at the remote end of the tube, said end portions of the carrier having clearance with the tube for lateral movement under the actuation of the cams.

8. A dispensing package including a carrier, a sleeve in which the carrier is slidable, the carrier and sleeve having closure means comprising tubular portions of which one is frictionally engaged in the other, one tubular portion having opposed sections spaced from the companion tubular portion to afford clearances interrupting the frictional surface of engagement, and one of the tubular portions being resilient and deformable under external hand pressure at said sections to thus reduce the pressure and friction to facilitate disengagement of the tubular portions for opening the closure means.

9. A dispensing package including a carrier having a row of pockets for receiving articles to be dispensed, a sleeve in which the carrier is slidable, said pockets having a cross section less than that of the sleeve so that the articles normally project from the pockets with the latter and the articles being of uniform relation in size and shape, said sleeve having a feeler projecting into the path of the articles above the pockets, said feeler being located at the open end of the sleeve and being adapted to frictionally engage edge portions of the articles to indicate the approach of an article to discharging position immediately beyond the said open end of the sleeve, the latter and the carrier having closure means for the open end of the sleeve so related to said feeler that the closure means is adapted to close without obstruction by the feeler and independently of the latter.

10. A dispensing package according to claim 9 wherein said feeler is integral with the sleeve, the sleeve having a resilient section of reduced thickness for resiliently mounting the feeler.

11. A dispensing package according to claim 8 wherein said carrier and sleeve have means for preventing relative rotation therebetween.

12. A dispensing package including a carrier, a sleeve in which the carrier is slidable, a first cam at the bottom of the leading end of the carrier projecting downward from the bottom of the carrier, a second cam at the bottom of the remote end of the sleeve and being located therein, the second cam projecting upward from the bottom of the sleeve, said carrier and sleeve being so coordinated with each other that intermediate of the cams, when the carrier is in open position, the carrier rests directly on the sleeve wall and is moved up by the cams when the carrier is moved into closed position in the sleeve, whereby articles in the carrier are moved into non-rattling contact with the sleeve.

13. A dispensing package according to claim 8 wherein cams are provided respectively on the carrier and sleeve, one at one end and the other at the other end of the package and cooperating to lift the carrier as the latter is moved into closed

position in the sleeve, said closure means having clearance for said lifting movement with the closure means being frictionally engaged when the cams are in operative engagement.

14. A dispensing package including a casing, a carrier slideable along a path therein, said carrier having compartment means for supporting articles so that the articles project from the carrier and are adapted to internally contact the casing, and means to cause a movement of the carrier at both of its ends laterally to said path to cause said articles to come into positive internal engagement with the casing to hold the articles against shifting in the carrier when the carrier is moved to closed position, including fixed cams on the respective carrier and casing at opposite ends of the package.

15. A dispensing package including a tubular casing, an article carrier slideable therein, the casing having an open end and having opposed internal projections at the open end, one of the projections being an article feeler and the other being a stop, the stop having a greater radial dimension than the feeler, the carrier having a closed-ended groove to receive the stop, and cam means whereby the carrier is bodily moved along the plane of said projections toward the side of the casing having the feeler when the carrier is moved to closed position in the casing, the cam means including a projecting cam on each of the casing and carrier, at opposite ends of the package.

CHARLES J. HAAG.
